EX

DESIGN FOR A COMB.

Design No. 12,337, dated July 5, 1881.

UNITED STATES PATENT OFFICE.

WILLIAM BYRON, OF NEW YORK, N. Y., ASSIGNOR TO THE VULCANITE JEWELRY COMPANY, OF SAME PLACE.

DESIGN FOR A COMB.

SPECIFICATION forming part of Design No. 12,337, dated July 5, 1881.

Application filed May 13, 1881. Term of patent 7 years.

To all whom it may concern:

Be it known that I, WILLIAM BYRON, of the city, county, and State of New York, have invented and produced a new and original Design for Combs, of which the following is a specification, reference being had to the accompanying photographic illustration, forming a part thereof.

The leading feature of my design consists of a curved bar inserted through and supported by transversely-perforated standards affixed to and projecting upwardly from the back of the comb, the curvature of the bar being such as to make it substantially parallel with the curved upper edge of the comb.

The accompanying photograph is a view of the convex or outer side of a back comb, A, in which my design is embodied.

To the curved upper edge, a, of the back of the comb there are affixed several standards, B B B, transversely perforated to admit the curved bar C, which is inserted through the perforations in the several standards. By means of the standards the bar is supported

at a short distance from the upper edge of the comb, and is substantially parallel therewith.

The back of the comb, the standards, and the bar may, if desired, be carved, engraved, or otherwise ornamented without departing from my design, the effect of which is to present to the eye a curved bar inserted through and supported by perforated standards at a short distance above the upper edge of the comb.

It will, of course, be understood that my design is equally applicable to either back combs or side combs.

I claim—

The design for a comb herein illustrated and described, the same consisting of the curved bar C, inserted through and supported by several transversely-perforated standards, B B B, affixed to and projecting upwardly from the upper edge of the back of the comb.

WILLIAM BYRON.
